DESIGN FOR A DISPLAY CONTAINER

Bernard F. Oshei, Buffalo, N. Y.

Application May 3, 1937, Serial No. 69,124

Term of patent 3½ years

To all whom it may concern:

Be it known that I, Bernard F. Oshei, a citizen of the United States, and residing at Buffalo, in the county of Erie and State of New York, have invented a new, original, and ornamental Design for a Display Container, of which the following is a specification, reference being had to the accompanying drawing forming part thereof.

In said drawing:

container showing my design with the cover open.

I claim:

The ornamental design for a display container as shown.

BERNARD F. OSHEI.
